UNITED STATES PATENT OFFICE.

JULIUS J. ACKER, OF CHICAGO, ILLINOIS; IRVIN D. ACKER ADMINISTRATOR OF SAID JULIUS J. ACKER, DECEASED, ASSIGNOR OF ONE-HALF TO GEORGE S. GOODWIN, OF CHICAGO, ILLINOIS.

OPERATING DEVICE FOR COUPLING PINS.

Application filed August 15, 1921. Serial No. 492,220.

To all whom it may concern:

Be it known that I, JULIUS J. ACKER, a citizen of the United States, and a resident of Chicago, Cook County, Illinois, have invented certain new and useful Improvements in Operating Devices for Coupling Pins, of which the following is a specification.

The present invention relates to devices for operating the locking devices or pins of railway car couplings and seeks to provide a simple, inexpensive construction which will not bind or become bent or broken by the movements of the coupling with respect to the car body. The invention consists in the features of improvement hereinafter set forth, illustrated in the accompanying drawing and more particularly pointed out in the appended claims.

In the drawing:

20 Figs. 1 and 2 are side and end elevations respectively of portions of the car body and coupling with the present improvement applied thereto.

25 Figs. 3 and 4 are elevations at right angles to each other of the connecting link between the locking device or pin of the car coupling and its operating lever.

30 Fig. 5 is a view similar to Fig. 4 with the parts of the connecting link extended.

35 Fig. 6 is a section on the line 6—6 of Fig. 4.

The car coupling 10 is of common form and is provided with a locking device or pin 11 having a perforated upper end or eye. 40 The operating member or lever for the pin preferably comprises a rock shaft 12 journaled in bearing brackets 13 and 14 which are mounted upon the end of the car body 15. The shaft or lever has a depending arm or handle 16 at its outer end and an arm 17 at its inner end which projects horizontally from the end of the car body over the coupling 10.

45 The arm 17 has a perforated end or eye which is connected to the upper end or eye of the pin 11 by a link comprising relatively movable sections. The link sections are preferably formed of round iron or steel of suitable size and are preferably duplicates.

50 One end portion of each link section is shaped to form a substantially circular hook or eye 18 and the hooks of the link sections respectively engage the perforated ends or eyes of the lever arm 17 and of the coupling

pin 11. The opposite end portions or shanks 55 19 of the link sections overlap and extend through a connecting member or sleeve 20 which is adapted to limit the relative longitudinal movement of the link sections and also prevent excessive relative angular and rotary movements thereof.

Preferably, as shown, the shanks 19 are forged or otherwise so shaped that they are half-round in cross section as most clearly shown in Fig. 6, but preferably without reducing the cross sectional area of the round rods from which the link sections are formed. The shanks extend through the connecting sleeve 20 with their flat sides or faces in engagement and this sleeve can be conveniently formed of a short section of wrought iron or steel pipe. The latter loosely fits upon the shanks or overlapping portions 19 of the link sections and is adapted to cooperate with outturned lugs 21 on the ends of the shanks to limit the relative longitudinal movement of the link sections.

The parts of the improved device can be very economically made and assembled. In assembling the flexible connection between the coupling pin and its operating lever, it is only necessary to leave the shank 19 of one of the link sections straight throughout and bend its end to form a lug 21 after the shanks have been inserted in the connecting sleeve 20. The connection formed by the link sections and coupling sleeve is, of course, free to swing in different planes, that is to say both transversely and longitudinally of the car as the coupling 10 moves relatively to the car, and permits the up and down movement of the coupling with respect to the car without accidentally lifting the coupling pin. It should also be noted that, while the coupling sleeve loosely fits and is considerably shorter than the overlapping shanks 19 of the link sections, it is of sufficient length to prevent excessive relative angular movement of the link sections, and it also cooperates with the half-round shanks 100 to prevent excessive relative rotary movement of the link sections. In other words, the coupling sleeve is adapted to hold the link sections substantially in alignment and against substantially relative rotary movement, so that the parts cannot twist into such a position that they will bind. At the same time the connection between the link

sections is such that they can shift freely and the movement of the car coupling will not bring any breaking or bending strain thereon. Obviously, by lifting the handle 5 16 the lever arm 17 will be raised to take up the lost motion between the shanks of the link sections and the connecting sleeve and lift the locking device or pin of the coupling.

It should also be noted that the terminal 10 hooks or eyes on the link sections are considerably larger than the shanks and the connecting sleeve and like the lugs 21 at the opposite ends of the shank portions 19 serve to limit the sliding movement of the sleeve 15 upon the shanks. The arrangement is also such that the link sections are permanently connected by the sleeve 20.

Changes may be made in the details set forth without departure from the essentials 20 of the invention as defined in the following claims.

I claim as my invention:-

1. The combination with the locking device of a car coupling and an operating lever 25 therefor, of an extensible, freely movable link connection between said lever and said locking device comprising two sections and a member permanently connecting said link sections and holding the same substantially 30 in alignment and against substantial relative rotary movement but permitting relative longitudinal movement thereof, substantially as described.

2. The combination with a car coupling 35 locking pin and an operating lever therefor, of a freely swinging extensible link comprising sections engaging said pin and lever respectively, and a rigid member carried by and loosely engaging said link sections and 40 permanently connecting the same but permitting a limited relative longitudinal movement thereof.

3. The combination with a car coupling locking device and an operating lever there- 45 for, of an extensible, freely moving link comprising two sections having hook portions engaging said device and said lever and overlapping shank portions, and a sleeve substantially shorter than said shank por- 50 tions and through which the latter are slide- 55 able, said shank portions having lugs at their ends arranged to engage said sleeve, substantially as described.

4. The combination with a coupling pin 55 and its operating lever, of a freely swinging

extensible link connecting said pin and lever and comprising two overlapping sections and a rigid sleeve loosely surrounding and permanently connecting said sections and adapted to hold the same substantially in alignment and against substantial relative rotary movement but permitting a relative longitudinal movement thereof, substantially as described.

5. The combination with a car coupling 65 pin and its operating lever, of an extensible, freely swinging link comprising sections engaging said pin and lever respectively, said sections having overlapping shank portions, and steps and lugs at the opposite ends of 70 said shank portions and a sleeve relatively shorter than said shank portions loosely mounted thereon between said lugs and stops.

6. The combination with a car coupling 75 pin and its operating lever, of an extensible, freely swinging link comprising sections pivoted respectively to said pin and lever and having overlapping shank portions pro- 80 vided with out-turned lugs at their ends, and a sleeve substantially shorter than said shank portions and loosely mounted thereon between said lugs and adapted to cooperate therewith to permit a limited relative longitudinal movement of said link sections and hold the latter against excessive relative angular and rotary movements, substantially as described.

7. The combination with a coupling pin 85 and its operating lever, of two link sections 90 comprising hook portions engaging said pin and lever respectively, and half-round overlapping shank portions provided with out- 95 turned end lugs and a cylindrical sleeve sub- stantially shorter than said shank portions and loosely mounted thereon between said lugs and serving to permanently connect said link sections while permitting a limited lon- 100 gitudinal movement thereof.

8. The combination with a coupling pin 100 and its operating lever, of an extensible link comprising sections pivoted to said pin and lever respectively to swing freely in different directions, said link sections being provided with half-round shank portions having flat 105 engaging faces and outwardly projecting lugs, and a rigid, cylindrical sleeve substan- tially shorter than said shank portions and loosely mounted thereon between said lugs.

JULIUS J. ACKER.
